CLAIM

The ornamental design for a collapsible bag, as shown and described.

DESCRIPTION

FIG. 1 is a front perspective view of a collapsible bag, showing my new design in an expanded and closed configuration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is a front perspective view thereof, illustrated in an expanded and open configuration;

FIG. 9 is a front perspective view thereof, illustrated in a partially collapsed configuration;

FIG. 10 is a front perspective view thereof, illustrated in a collapsed configuration;

FIG. 11 is a perspective view of FIG. 10;

FIG. 12 is a rear perspective view of FIG. 10; and,

FIG. 13 is a rear perspective view of FIG. 10.

The broken lines in FIGS. 1, 2, and 12 depicting a logo emblem depict portions of the collapsible bag that form no part of the claimed design. The remaining broken lines depict stitching, and do form part of the claimed design.
